J. A. COSTELLO

FAUCET

Filed July 3, 1924

Inventor:
Joseph A. Costello

By Charles Warner

his Attorney.

UNITED STATES PATENT OFFICE.

JOSEPH A. COSTELLO, OF CLEVELAND, OHIO, ASSIGNOR TO THE CLEVELAND BRASS MANUFACTURING COMPANY, OF CLEVELAND, OHIO, A CORPORATION OF OHIO.

FAUCET.

Application filed July 3, 1924. Serial No. 724,149.

To all whom it may concern:

Be it known that I, JOSEPH A. COSTELLO, a citizen of the United States, residing at Cleveland, in the county of Cuyahoga and 5 State of Ohio, have invented a new and useful Faucet, of which the following is a specification.

This invention relates to improvements in faucets, and pertains more especially to a 10 faucet well adapted for use in connection with a metal oil-barrel and comprising a casing having an interior chamber which has a fluid-outlet and a fluid-inlet which is surrounded by a seat for a valve employed 15 in controlling communication through said inlet and having a sliding or rectilinear movement from an open position to said seat and capable, after said movement of the valve into engagement with said seat, of a 20 limited rotation to the right and adapted to be forced, during said rotation, into fluid-tight engagement with said seat.

One object of this invention is to provide 25 a faucet of the character indicated with conveniently applied resilient means acting to retain said valve in engagement with the valve-seat without being materially interfered with by and without interfering with the hereinbefore mentioned rotation of the 30 valve.

Another object is to avoid the necessity of 35 manually holding the valve in an open position against the action of said resilient means throughout the time required for the run of a given quantity of liquid from the hereinbefore mentioned inlet to and through the aforesaid outlet.

Another object is to produce a faucet of 40 the character indicated which comprises simple and efficient means for preventing material or objectionable circumferential displacement of the valve during the aforesaid endwise movement of the valve and without interfering with a satisfactory dis- 45 charge of all liquid entering the hereinbefore mentioned chamber from the faucet at the hereinbefore mentioned outlet.

Another object is to facilitate the man- 50 ufacture and assemblage of the component parts of the faucet, and to render the faucet highly practical and simple and durable in construction.

With these objects in view, and to attain 55 other objects hereinafter appearing, this in- vention consists in certain features of con-

struction, and combinations and relative arrangements of parts, hereinafter described in this specification, pointed out in the claims, and illustrated in the accompanying drawings.

In said drawings, Figure 1 is a view which is largely a central vertical longitudinal section of the faucet, but the valve is shown partly in elevation and also as in position engaging the valve-seat preparatory to 65 pressing the valve tightly against said seat. Fig. 2 is a view similar to Fig. 1 but shows the valve as having been actuated to tightly press the valve against the valve-seat. Figs. 3, 4 and 5 are transverse sections taken 70 along the line 3-3, line 4-4 and line 5-5, respectively, in Fig. 1, looking rearwardly. Fig. 6 is a transverse section taken along line 6-6 in Fig. 2, looking rearwardly. Fig. 7 is a view similar to Fig. 1 but shows 75 the valve as having been actuated forwardly into an open position before the required limited rotation of the valve to the right 80 for the purpose, as will hereinafter appear, of holding the valve in the desired open position by means internally of the valve-casing. Fig. 8 is a view similar to Fig. 7 but shows the valve as being held open by said means internally of the valve-casing. Figs. 9 and 10 are transverse sections taken along 85 line 9-9 and line 10-10, respectively, in Fig. 8, looking forwardly. Portions are broken away in the drawings to reduce their size and to more clearly show the construction.

Referring to said drawings, A indicates the metal casing of the faucet, and said casing comprises a substantially horizontal and externally screw-threaded tubular member 11 adapted to be threaded into and to extend 90 forwardly from the head of a metal oil-barrel not shown. Said casing extends upwardly and forwardly from said tubular member 11 and has an interior chamber 12 having a fluid-outlet 13 formed at the bottom of the casing and adjacent the forward end of said member 11. The casing is internally provided, at the rear end of the chamber 12, with a forwardly and upwardly projecting annular member 15 arranged to 95 form a forwardly and somewhat upwardly facing valve-seat rearward of and higher than the outlet 13. Said chamber extends forwardly and upwardly from the valve-seat-member 15 and has a fluid-inlet formed by 100 110

an aperture 16 in and centrally of the rear end wall of said chamber. Said inlet 16 is surrounded by the valve-seat, and the chamber 12 extends rearwardly, as at 17, 5 around said seat.

My improved faucet comprises a valve arranged to control communication through the fluid-inlet 16 of the chamber 12 and having a metal body comprising a rigid core 18 which is arranged substantially centrally and extends endwise of and is surrounded by said chamber. On the rear end of said core 18 is formed a circular head 19 which has bearing in the casing in any position of 10 the valve. Said head 19 is provided, at its rearward side, with a disk or member 21 secured in place in any approved manner and preferably composed of elastic and compressible material such, for instance, as rubber and arranged to form the face of the valve. On the forward end portion of the core 18 is formed a circular head 22 which has bearing in the casing when the valve is in position engaging the valve-seat, as shown 15 in Figs. 1 and 2. The forward head 22 has a member 23 arranged externally of the casing in any position of the valve and contoured to form a handle for manipulating the valve.

30 Said valve has a sliding or substantially rectilinear endwise movement to and from the valve-seat. When the valve is in an open position and therefore spaced forwardly from the inlet 16, as shown in Figs. 35 7 and 8, the rearward head 19 has bearing in the casing forward of the outlet 13, and the forward head 22 of the valve is out of and spaced forwardly from the casing. As shown in Figs. 1 and 2, the forward head 40 22 forms a closure for the forward end of the chamber 12 when the valve is in engagement with the valve-seat. At the end of its endwise movement from an open position to the valve-seat the valve is capable 45 of a limited rotation to the right and forceable, as will hereinafter appear, into fluid-tight relation to said seat during said rotation of the valve.

50 The core 18 has a circumferential annular baffle-flange 25 disposed between and spaced from the heads 19 and 22 and contained within the chamber 12 in both closed and open positions of the valve and arranged to have bearing in the casing in any 55 position of the valve.

60 The core 18 also has a circumferential flange 27 arranged between and spaced from the forward head 22 and baffle-flange 25 and preferably having bearing, at its circumference, in the casing in any position of the valve. The flange 27 has a forwardly facing surface 28 extending circumferentially and endwise of the axis of the valve.

65 The casing is provided, preferably at the top thereof, with a pin 29. Said pin is

spaced forwardly from the baffle-flange 25 and shown arranged near but rearwardly from the forward extremity of the casing. Said pin is substantially radial in relation to the valve and threaded into the casing 70 and has a plain inner end portion arranged in the chamber 12 between the forward head 22 and the baffle-flange 25.

The core 18 (see Figs. 1, 4, 5, 6, 7 and 9) has a flange 31 which is substantially parallel with the hereinbefore mentioned sliding or substantially rectilinear endwise movement of the valve and extends preferably from the forward side of the baffle-flange 25 forwardly to the forward head 22. 75

The core 18 (see Figs. 1, 2, 4, 7, 8 and 9) has a flange 32 which is spaced leftward circumferentially of the core from the flange 31 preferably a distance less than one-half the distance around the core and extends 80 rearwardly from the rear side of the flange 27. The flange 32 is arranged wholly forward of the baffle-flange 25 and spaced from said baffle-flange a distance which measures less than the diameter of the pin 29. Preferably the flange 27 extends from the forward extremity of the flange 32 in opposite directions circumferentially of the core 18 and has one end thereof at the right-hand side of the flange 31 and has its other end 85 terminating in a transverse edge 33 between the left-hand side of the flange 31 and the forward extremity of the flange 32. The flange 27 therefore extends from the flange 31 at one side of the core 18 rightward circumferentially and to the opposite side of the core and is contoured and arranged to clear the pin 29 during the actuation of the valve from one end to the other end of the hereinbefore mentioned rectilinear movement of the valve. 90

100 The relative arrangement of the parts is such that the flange 31 is opposite the right-hand side of and substantially next to the pin 29 when the valve is in the positions shown in Figs. 1 and 7 and throughout endwise movement of the valve from one to the other of said positions, that during said movement of the valve said flange 31 is 105 adapted to cooperate with the right-hand side of said pin in guiding the valve and in preventing material or objectionable leftward circumferential displacement of the valve, that the surface 28 of the flange 27 extends from the transverse edge 33 of the flange 27 leftward circumferentially of the core 18 and somewhat in a forward direction to the right-hand side of the flange 31, that said surface 28 and the rear side or 110 surface of the pin 29 are therefore relatively arranged as required to cooperate in pressing or forcing the valve into fluid-tight relation to the valve-seat during the rotation of the valve to the right after the valve has 115 been moved endwise from an open position 120

to said seat, and obviously when the valve is in its tightly closed position shown in Fig. 2, after said rotation of the valve, a forceable turn of the valve to the left will 5 be required preliminary to movement of the valve into an open position.

The upper portion of the rearwardly facing forward wall of the outlet 13 projects rearwardly of the lower portion of said wall 10 and has a rearwardly facing and preferably substantially vertical surface 34 arranged to form a baffle and spaced forwardly from and opposite and extending lower than the inlet 16 of the chamber 12 and adapted to 15 minimize the liability of the discharge of liquid directly from said inlet into the lower end of a drain-passage 35 which is formed in the casing and extends from the bottom of said chamber, at a point spaced forwardly from the inner end of the outlet 13, substantially vertically downwardly to said outlet and discharges at its lower end into 20 said outlet next below the bottom 36 of said projecting upper portion of said wall.

25 Preferably the relative arrangement of the parts is such that the passage 35 communicates, rearward of the flange 27, with the chamber 12 in any position of the valve; that said passage communicates with said 30 chamber between said flange 27 and the baffle-flange 25 when the valve engages the valve-seat, as shown in Figs. 1 and 2; that said baffle-flange has bearing in the casing forward of the inner end of the outlet 13 35 and between said end of said outlet and the upper end of the passage 35 when the valve is in engagement with said seat; that said baffle-flange is rearward, in any position of the valve, of the means (surfaces 28 and pin 40 29) for forcing the valve into fluid-tight relation to said seat, and that the passage 35 is in communication, at its upper end, with the chamber 12 between the rearward head 19 and the baffle-flange 25 when the valve 45 is in an open position, as shown in Figs. 7 and 8.

50 During the actuation of the valve from its valve-seat-engaging position shown in Fig. 1 to the open position shown in Fig. 7 the baffle-flange 25 obstructs the passage, in the direction of the forward end of the chamber 12, of the liquid passing forwardly in said chamber at the inner end of the outlet 13. However, during the rush or flow of liquid 55 at the rear end of and into the chamber 12 during the opening of the valve, and more especially during the flow of liquid under pressure into said chamber, the passage of some liquid forwardly at the inner end of 60 the outlet 13 and transversely of the outer circumferential edge of the baffle-flange 25 in the direction of the forward end of said chamber is not impossible, because the use of packing is avoided and said flange is not, 65 therefore, in fluid-tight relation to the cas-

ing. Obviously the rush or flow of liquid through the outlet 13 from the inlet 16 in an open position of the valve results in the creation of suction within the passage 35, so that any liquid passing forwardly at the 70 upper end of the baffle-surface 34 and between the rearward head 19 and baffle-flange 25 in opening the valve, or in an open position of the valve, is drawn by said suction into said passage. Said suction, the drain- 75 passage 35, the baffle-surface 34 and the hereinbefore described arrangement of said passage in relation to said chamber and to said baffle-surface participate in effecting satisfactory drainage, through said passage, of 80 liquid which has passed to and forwardly of the forward head 19 when the valve has been opened as shown in Figs. 7 and 8.

85 My improved faucet comprises resilient means acting to retain the valve in engagement with the valve-seat so as to obstruct the flow of liquid through the inlet 16 of the chamber 12 and to minimize the loss of liquid should the valve carelessly not have been actuated from the position shown in 90 Fig. 1 into fluid-tight relation to said seat as shown in Fig. 2, and said resilient means preferably comprise a coiled spring 37 which (see Figs. 1 and 7) is arranged internally 95 and extends endwise of the tubular member 11 and is attached at its rear end to said member 11 and at its forward end to the valve. Preferably the member 11 is provided internally of its lower portion, near the rear extremity of said member 11, with a 100 lug 38 projecting inwardly and toward said extremity of said member 11, and the spring 37 embraces and is removably connected to said lug. Said spring is shown attached, at its forward end, to the head of a screw 105 39 employed in securing the valve-face-forming member 21 to the forward head 19 of the core 18. Obviously the actuation of the valve from its valve-seat-engaging position shown in Fig. 1 into the open position 110 shown in Fig. 7 is against the action of the spring 37, and said spring is not materially interfered with by and does not interfere with the hereinbefore mentioned limited rotation of the valve.

115 It will be observed that the valve, upon actuating it from its valve-seat-engaging position shown in Fig. 1 into the open position shown in Fig. 7, has been moved far enough forwardly endwise to bring the 120 flange 27 of the core 18 wholly forward of the pin 29, and the relative arrangement of the parts is preferably such that, when the valve is in position with the flange 31 next said pin, as shown in Fig. 5, the hereinbefore mentioned transverse edge 33 of 125 said flange is at the top of the core and substantially horizontal and spaced leftward from the flange 31 and wholly below the pin 29, and that the valve, when it has 130

been actuated from the position shown in Fig. 1 into the position shown in Fig. 7, is capable of limited rotation to the right until the flange 32 abuts against the pin 29. 5 Obviously therefore, the left-hand side of the pin 29 and the flange 32 cooperate in forming a stop for limiting manual rotation of the valve to the right after endwise actuation of the valve into the open 10 position shown in Fig. 7 from the valve-seat and the relative arrangement of the parts is such that, during said limited rotation of the valve to the right after the valve has been actuated to said open position, the flange 27 is brought forward of and opposite the forward side of the pin 29, as shown in Fig. 9, so that the valve, 15 after releasing it from manual hold after said rotation of the valve, is pulled rearwardly by the spring 37 so as to bring the rear side of said flange 27 into pressure-exerting relation to the forward side of said pin and thereby cause the valves to be effectively held in the open position shown 20 in Fig. 8 and against the action of said spring. Obviously the valve, to return it to its valve-seat-engaging position shown in Fig. 1 after the actuation of the valve into the position shown in Fig. 8, is, first, manually rotated to the left from the position 25 shown in Fig. 8 into the position shown in Fig. 7, whereupon the release of the valve from manual hold renders the valve free to be moved rearwardly by the spring 37 30 by which said valve is then returned into the position shown in Fig. 1.

What I claim is—

1. A faucet comprising a casing having an 40 internal valve-seat and an interior chamber which has a fluid-outlet adjacent and a fluid-inlet surrounded by said seat, a valve controlling communication through said inlet and having a substantially rectilinear movement and engaging said seat at one end of 45 said movement and in an open position at the other end of said movement and capable of rotation when the valve is at the last-mentioned end of said movement, a coiled spring acting to retain the valve in 50 engagement with said seat, and means arranged to prevent movement of the valve from said open position to said seat after the required rotation of the valve when the valve has been moved from said seat to said 55 open position, the casing having a tubular member which communicates with and extends rearwardly of the aforesaid inlet and has a lug internally of its lower portion, and the aforesaid spring being attached at 60 its rearward end removably to said lug and at its forward end to the valve.

2. A faucet comprising a casing having an internal valve-seat and an interior chamber which extends forwardly from said seat 65 and has a fluid-outlet adjacent and a fluid-

inlet surrounded by said seat, a valve controlling communication through said inlet and having a substantially rectilinear movement from and toward said seat and engaging said seat at one end of said movement and in an open position at the other end of said movement and capable of rotation when the valve is at the last-mentioned end of said movement and comprising a core which extends endwise of and is surrounded by the aforesaid chamber, and a pin rigid with the casing and spaced forwardly from the inner end of the core, said core and said pin having cooperating surfaces arranged to prevent movement of the valve from the aforesaid open position to said seat after the required rotation of the valve when the valve has been moved from said seat to said open position.

3. A faucet comprising a casing having an internal valve-seat and an interior chamber which extends forwardly from said seat and has a fluid-outlet adjacent and a fluid-inlet surrounded by said seat, a valve controlling communication through said inlet and having a substantially rectilinear movement and engaging said seat at one end of said movement and in an open position at the other end of said movement and capable of rotation at each end of said movement and comprising a core which extends endwise of and is surrounded by the aforesaid chamber, and a pin rigid with the casing and spaced forwardly from the inner end of the core, said core and said pin having cooperating surfaces arranged to force the valve into fluid-tight relation to the aforesaid seat during the required rotation of the valve when the valve has been actuated to said seat from the aforesaid open position, and said pin and said core also having cooperating surfaces arranged to prevent movement of the valve from said open position to said seat after the required rotation of the valve when the valve has been moved from said seat to said open position.

4. A faucet comprising a casing having an internal valve-seat and an interior chamber which extends forwardly from said seat and has a fluid-outlet adjacent and a fluid-inlet surrounded by said seat, a pin rigid with the casing and extending into said chamber, a valve controlling communication through said inlet and having a substantially rectilinear movement and engaging the aforesaid seat at one end of said movement and in an open position at the other end of said movement and comprising a core which extends endwise of and is surrounded by said chamber and has a flange extending circumferentially of the core from one side to the opposite side of the core and contoured and arranged to clear said pin during said movement of the valve, and resilient means acting to retain the valve in

tially rectilinear movement and engaging said seat at one end of said movement and in an open position at the other end of said movement and comprising a core which extends endwise of said chamber and has a longitudinal flange opposite the right-hand side of the aforesaid pin throughout said movement of the valve and also has an annular baffle-flange at the rear end of said longitudinal flange and a circumferential flange extending from said longitudinal flange rightward circumferentially of the core and contoured and arranged to clear

said pin during said movement of the valve, the valve being capable of limited rotation 15 to the right when the valve has been moved to the aforesaid open position, and the third-mentioned flange being in position to move forward of the forward side of the aforesaid pin during said rotation of the 20 valve after movement of the valve to said open position.

In testimony whereof, I sign the foregoing specification.

JOSEPH A. COSTELLO.
